UNITED STATES PATENT OFFICE.

STANLEY M. SOVOCOOL, OF ADDISON, NEW YORK.

CLOTHES-PIN.

1,120,166.

Specification of Letters Patent.

Patented Dec. 8, 1914.

Application filed October 25, 1913. Serial No. 797,313.

To all whom it may concern:

Be it known that I, STANLEY M. Sovocool, a citizen of the United States, residing at Addison, in the county of Steuben and State of New York, have invented certain new and useful Improvements in Clothes-Pins, of which the following is a specification, reference being had to the accompanying drawings.

10 This invention relates to certain improvements in clothes pins and has for its object to provide a device of this general character produced from a single strand of wire.

The invention consists in the details of 15 construction and in the combination and arrangement of the several parts whereby certain important advantages are attained and the device is rendered simpler, less expensive and otherwise more convenient and 20 vantageous for use, all as will be herein-after more fully set forth.

The novel features of the invention will be carefully defined in the appended claims.

In order that my invention may be the 25 better understood, I will now proceed to describe the same with reference to the accompanying drawings, wherein—

Figure 1 is a view in elevation of a clothes pin constructed in accordance with an embodiment of my invention; Fig. 2 is a view in end elevation of the device as illustrated in Fig. 1, showing the relation of the parts; Fig. 3 is a view similar to Fig. 1, showing the device but partly assembled; and Fig. 35 4 is a view similar to Figs. 1 and 3 showing the initial step in producing a clothes pin in accordance with the embodiment as herein contained.

As disclosed in the accompanying drawings, 40 1 denotes a strand of wire, of requisite gage and possessing a certain degree of resiliency, which is initially flexed or bent upon itself at substantially its center, as indicated at 2, to produce a bowed portion 45 substantially semi-circular in form. At a predetermined point below the flexed or bowed portion 2, the strands are twisted, as at 3, one about the other with such twisted portion substantially central of the bowed 50 or flexed portion 2, the adjacent portions of such strands being abruptly curved so that

the intermediate portions 4 will be substantially in parallel relation as will the remaining portions 5 thereof. It is to be observed that the flexure 2 is so produced initially as 55 to have one of the strands of greater length than the other so that the projected portion 6 thereof may be flexed in substantially a semi-circular manner and have its free extremity welded or otherwise permanently 60 secured to the free extremity of the second strand.

The twisted portion 3 is flexed or bent in such a manner as to bring the smaller loop afforded by such twisted portion substantially parallel with the second or elongated loop and it is to be observed that such shorter loop is of such a length as to extend sufficiently along the greater loop as to effectually bridge a clothes line or the like to 70 properly clamp an article thereto.

From the foregoing, it is thought to be obvious that a clothes pin constructed in accordance with my invention is of an extremely simple and comparatively inexpensive nature and is particularly well adapted for use by reason of the convenience and facility with which it may be applied in operative position and it will also be obvious that my invention is susceptible of some 75 change and modification without material departure from the principles and spirit thereof and for this reason I do not wish to be understood as limiting myself to the precise arrangement and formation of the several parts herein shown in carrying out my invention in practice.

Having thus fully described my invention what I desire to claim and secure by Letters Patent is:

1. A clothes pin produced from a single piece of wire bent intermediate its length to produce parallel strands, the free extremities of such strands being permanently united, such strands being twisted one about 90 the other intermediate their lengths to afford two loops, said loops being bent so that said twisted portion is disposed at right angles to the loops to bring such loops into substantial parallel relation, such loops being normally spaced one from the other 95 throughout their entire length.

2. A clothes pin produced from a single piece of wire bent intermediate its length to produce parallel strands, said strands being twisted one about the other at a point intermediate their lengths to afford a loop, said loop and the opposite extremity of the pin being bent so that said twisted portion is disposed at right angles thereto, said loop

being normally spaced from said opposite extremity of the pin throughout its length. 10

In testimony whereof I hereunto affix my signature in the presence of two witnesses.

STANLEY M. SOVOCOOL.

Witnesses:

FRANK S. WHITMORE,
E. A. Sovocool.
